UNITED STATES PATENT OFFICE

120,376

DESIGN FOR A KNITTED TEXTILE FABRIC OR SIMILAR ARTICLE

Max Doft, Lawrence, N. Y., assignor to Princeton Knitting Mills, Incorporated, a corporation of Connecticut

Application January 26, 1940, Serial No. 89,737

Term of patent 3½ years

To all whom it may concern:

Be it known that I, Max Doft, a citizen of the United States of America, and resident of the town of Lawrence, county of Nassau, and State of New York, have invented a new, original, and ornamental Design for a Knitted Textile Fabric or Similar Article, of which the following is a specification, reference being had to the accompanying drawing, forming a part thereof.

The figure is a plan view on an enlarged scale of a piece of knitted textile fabric or similar article showing my new design.

I claim:

The ornamental design for a knitted textile fabric or similar article, as shown.

MAX DOFT.
